Application filed September 8, 1930. Serial No. 36,909. Term of patent 14 years.

To all whom it may concern:

Be it known that I, CHARLES FLETCHER, a citizen of the United States, residing in Chicago, county of Cook, and State of Illinois, have invented a new, original, and ornamental Design for a Drinking Glass, of which the following is a specification, reference being had to the accompanying drawings forming part thereof.

In the drawings—

Figure 1 is a perspective view of a drinking glass, showing my new design;

Figure 2 is a sectional view in elevation thereof, taken on the line 2—2 of Fig. 1.

The dominant feature of my design resides in the blending of curves with a straight flaring bottom region to impart a distinctive configuration to a drinking glass.

I claim:

The ornamental design for a drinking glass as shown and described.

Chicago, Illinois, August 27th, 1930.
